UNITED STATES PATENT OFFICE.

FREDERICK B. HEMINGWAY, OF CLINTON, IOWA, ASSIGNOR TO HEMINGWAY & KELLY, OF SAME PLACE.

DEVICE EMPLOYED IN THE MANUFACTURE OF SPRING-BOTTOMS OF LOUNGES AND OTHER ARTICLES OF FURNITURE.

SPECIFICATION forming part of Letters Patent No. 380,323, dated April 3, 1888.

Application filed August 26, 1887. Serial No. 247,947. (No model.)

To all whom it may concern:

Be it known that I, FREDERICK B. HEMINGWAY, a citizen of the United States of America, residing at Clinton, in the county of Clinton 5 and State of Iowa, have invented certain new and useful Improvements in the Manufacture of Lounges, Sofas, Beds, Chairs, and other Articles of Furniture, of which the following is a specification, reference being had therein 10 to the accompanying drawings.

The invention relates to devices employed in the manufacture of spring-bottoms of lounges and other articles of furniture.

It is well-known that there is considerable 15 slack in the wires forming the loops and coils of ordinary wire webbing, and that owing to this slackness of the wires mattresses and supporting-bottoms made of such wire webbing invariably sag in use.

20 The object of the invention is to prevent the sagging of wire webbing, and especially such webbing employed as supporting - bases of spring-bottoms of lounges, sofas, beds, chairs, and other articles of furniture; and this invention 25 consists of devices adapted to stretch tightly the wire webbing used for such purposes, and adapted to hold such webbing in a tightly-stretched condition while it is being fastened to a frame, as fully set forth and claimed 30 in this application. While in this case these devices are illustrated in their application to stretching and attaching wire webbing to a lounge-frame, it is evident that without departing from the principle of the invention they 35 may be employed in stretching tightly and fastening wire webbing in the tightly-stretched condition to any frame where such webbing may be used, and where it may be desirable to prevent its sagging.

40 In the accompanying drawings, Figure 1 is a plan view of a lounge-frame, showing a plan of the stretcher and the wire webbing unstretched in full lines and stretched in dotted lines. Fig. 2 is a longitudinal section showing 45 in elevation the stretcher in position to stretch the webbing longitudinally. Fig. 3 is a plan view showing the stretcher placed crosswise in position to stretch the webbing sidewise. Fig. 4 is a cross-section of the same.

50 A designates the wire-web base cut or formed

sufficiently less in size than the frame to which it is attached to allow for expansion.

B designates a lounge-frame provided at one end with the transverse fulcrum-bar *d*, which is rigidly attached to the frame in position to 55 form the bearing of the free end of one section of the stretcher-bar, as herein set forth.

The stretching devices which at present I employ are adapted to stretch the wire webbing in one direction at a time, and they consist of 60 a stretcher, C, and a bench, D. The stretcher-bar is constructed in two parts, *a a'*, hinged together at *a'*. One end of this jointed bar is provided with a cross-head, *a³*, having fingers *a⁴*, consisting of iron rods bolted at one end to 65 the cross-head and having central grooves in their free ends formed parallel with the head to receive and hold against the rods *b b'*, inserted loosely through the meshes of the webbing. This stretcher is provided with a lever-bar in two parts, *b² b³*, the inner end of *b²* being firmly bolted to the hinged section *a* of the stretcher-bar, and the two parts of the lever are hinged together at *b⁴*, to allow part *b³* to be 70 folded back out of the way of the workman in fastening the webbing to the frame. The said bench consists of a supporting-frame having 75 projections *c*, forming a seat for a frame for holding it in place during the operation of stretching and fastening to the frame the wire webbing. This bench is provided with a fly, E, hinged to one side of the bench, and the free edge of this fly is provided with a fulcrum-bar, *c'*, extended above the upper surface of the fly, which bar forms a bearing for the free end of 80 section *a* of the stretcher-bar in stretching the webbing sidewise, as hereinafter fully explained. One end of the wire web being fastened to the end of the frame having the fulcrum-bar *d*, and the rod *b* being inserted 85 through the meshes of the web at or near its free end, the stretcher is placed upon the web with the free end of the section *a* of the stretcher-bar against the fulcrum-bar *d*. Then the jointed bar *a a'*, being constructed the required 90 length, is sprung upward in the middle sufficiently to draw the fingers inward to allow their grooved ends to catch against the rod *b*, as shown in Figs. 1 and 2 of the drawings.

95 Pressure being then applied upon the free end 100

of the lever, bearing down the jointed bar stretches tightly the wire webbing longitudinally, and then the adjustable keeper d' is moved along the hinged stretcher-bar, so as to 5 secure the stretcher in position, holding the wire expanded while its free end is being fastened to the frame.

In stretching the webbing sidewise, one side edge of the web being fastened to the side of 10 the frame toward the fulcrum-bar c' , and the bar b' being inserted through the meshes at or near the free edge of the wire web, the stretcher is placed crosswise of the webbing, with the free end of the section a of the jointed bar against the fulcrum-bar c' on the fly and the grooved 15 ends of the fingers bearing against the rod b' , and the stretching is then performed precisely in the same manner as above described. The hinged fly may be supported in a horizontal 20 position by a hinged leg, c^2 , and when not in use the fly may be folded down by the side of the bench.

Heretofore wire webbing employed in 25 spring-bottoms has been attached to separate frames and tightened (if tightened at all) by means of adjustable bars. I dispense with such separate frames and adjustable bars and attach the tightly-stretched wire base directly to the main frame, and thus save expense in 30 the manufacture and improve the quality of such articles, and avoid the liability of insects or mice entering and harboring in such spring-bottoms.

The wire webbing stretched tightly and attached in its tightly-stretched state to a frame, 35

as herein set forth, is not claimed in this application, but is made the subject of another application, No. 259,595, filed January 3, 1887.

What I claim as new is—

1. The wire-web stretcher consisting of the 40 jointed bar $a\ a'$, having the cross-head a^3 , provided with fingers a^4 , adapted to hold against rods inserted through the meshes of a wire web, A, the jointed lever $b^2\ b^3$, attached to the stretcher-bar, and the adjustable keeper d' , in 45 combination with supporting-frame B, a fulcrum-bar, d , attached to the frame and adapted to support one end of the stretcher-bar, and loose rods inserted through the meshes of the wire web, substantially as and for the purposes 50 described.

2. The bench D, provided on its top with a seat adapted to hold the frame of a lounge or other article of furniture, and having a hinged fly, E, provided with the fulcrum-bar c' , in 55 combination with the wire-web stretcher consisting of the jointed bar $a\ a'$, having the cross-head a^3 , provided with fingers a^4 , adapted to hold against rods inserted through the meshes of a wire web, A, the jointed lever $b^2\ b^3$, attached to the stretcher-bar, and the adjustable keeper d' , substantially as and for the purposes 60 described.

In testimony whereof I have affixed my signature in presence of two witnesses.

FREDERICK B. HEMINGWAY.
